(57) **CLAIM**

The ornamental design for a protective cover for tablet, as shown and described.

DESCRIPTION

FIG. 1 is a perspective view of a protective cover for tablet showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the protective cover for tablet shown in a configuration of use;

FIG. 10 is another perspective view of the protective cover for tablet shown in the configuration of use;

FIG. 11 is another perspective view of the protective cover for tablet shown in the configuration of use;

FIG. 12 is another perspective view of the protective cover for tablet of FIG. 1, shown in the configuration of use with an environmental tablet; and,

FIG. 13 is another perspective view of the protective cover for tablet of FIG. 1, shown in the configuration of use with additional environmental trinkets.

The broken lines in FIGS. 12 and 13 showing the tablet and the trinkets depict environment and form no part of the claimed design. The other broken lines in the drawings depict portions of the protective cover for tablet that form no part of the claimed design.

1 Claim, 13 Drawing Sheets
